UNITED STATES PATENT OFFICE.

JULIUS OLESCHAK, OF PHILADELPHIA, PENNSYLVANIA.

POCKET FOR GARMENTS.

No. 862,992.

Specification of Letters Patent.

Patented Aug. 13, 1907.

Application filed May 7, 1906. Serial No. 315,484.

To all whom it may concern:

Be it known that I, JULIUS OLESCHAK, a citizen of the United States, residing at Philadelphia, in the county of Philadelphia and State of Pennsylvania, have invented certain new and useful Improvements 5 in Pockets for Garments, of which the following is a specification.

My invention has reference to the fastening of the upper flap or opening in the pockets of garments and 10 consists of a set of stiffening pieces so constructed and arranged as to interlock and thereby tightly close the opening of the pocket for the purpose of guarding the contents against loss.

My invention will be more fully understood by reference to the accompanying drawings in which:

Figure 1 represents a side elevation of a portion of a garment with the device forming the subject matter of this invention arranged in position as indicated by dotted lines. Fig. 2 illustrates a vertical section of 20 the same as taken on a line 2—2 of Fig. 1. Fig. 3 shows a perspective view of one of the plates adapted to close the pocket. Fig. 4 represents a similar view of the same plate viewed from the opposite side. Fig. 5 illustrates a perspective view of another of the plates 25 which is adapted to engage the first mentioned plate. Fig. 6 illustrates a perspective view of the plates shown in Figs. 3 and 5 as brought together in a locking position, and Fig. 7 shows a perspective view of the structure illustrated in Fig. 5 slightly modified.

30 In this case the thin plate containing the hook is replaced by a wire structure in which the hook and support are one and the same piece.

Referring to the reference letters of the drawings: A, represents the garment; B, the pocket, and C the 35 hem arranged at the mouth or opening thereof. The hem C, is provided with a stiffening piece D, made of a thin strip of metal which is provided at the ends with small holes e, e, etc. by which the piece is fastened to the hem and also with a hook D¹, which is 40 riveted or otherwise firmly fastened to the stiffening piece.

Arranged on the opposite side of the pocket is a similar stiffening piece E, which is likewise formed of a thin strip of metal having holes e, e, etc. to secure it 45 to the garment and an offset E¹ formed by depressing the strip of metal to a sufficient depth to allow the hook D¹ to enter.

The side walls in the depression of the stiffening piece E, have slots f, f, to receive and guide a wire rod

F, whose function is to engage the hook D, and confine it within the offset E¹, thus securely closing the opening of the pocket. The rod F, is formed of a piece of spring wire which is bent or folded to give additional flexibility and then secured to the stiffening piece E, by staples g, g.

The rod F, is provided with an eye F¹ which alone may be pulled down when it is desired to open the pocket, but as shown in the drawings I prefer to employ a cord, rod or chain as shown at H, which depending from the eye F¹ may be manually operated to release the hook D¹. In Fig. 7 I have shown a slightly modified form of stiffening piece in which the same is made by bending a strip of wire in the form of a rectangular frame D², which may readily be sewed to the garment and is provided with a hook D³ formed integral with the frame.

In opening my device to remove a watch or other article from the pocket the operator takes hold of the rod H, between the thumb and forefinger of one hand and pulling it downward releases the spring-pressed rod 70 F, from engagement with the hook D¹, while with the other hand he removes the watch. In replacing the watch and latching the pocket the hand used in removing the watch is pressed against the side of the pocket to hold the hook D¹, in place, the rod H, is then 75 released and by its own tension engages the hook D¹, to close the opening in the pocket.

Other modification of a like character may be made without departing from the scope of my invention.

Having described my invention what I claim and 80 desire to secure by Letters Patent is:

1. A closure for pockets comprising two strips of metal disposed at the mouth of the pocket, a hook secured to one of said strips midway between the ends thereof, an offset formed in the other of the strips to receive the 85 hook and a spring actuated rod passing through the offset and adapted to engage said hook.

2. A closure for pockets, comprising a strip of metal constituting a front member, and a corresponding strip constituting the back member, a hook formed upon the 90 front member midway between the ends thereof, an offset formed upon the back member to receive the hook and an elastic rod passing through openings in the side walls of the offset and adapted to engage the hook.

In testimony whereof I affix my signature in presence 95 of two witnesses.

JULIUS OLESCHAK.
